UNITED STATES PATENT OFFICE.

GEORGE KOVÁC, OF DETROIT, MICHIGAN.

DESIGN FOR A KNIFE.

48,496.

Specification for Design.

Patented Feb. 1, 1916.

Application filed October 13, 1915. Serial No. 55,739. Term of patent 7 years.

To all whom it may concern:

Be it known that I, GEORGE KOVÁC, a subject of the King of Hungary, residing at Detroit, in the county of Wayne and State of Michigan, have invented a new, original, and ornamental Design for a Knife, of which the following is a specification, reference being had to the accompanying drawing, forming part thereof.

The figure is a view in perspective of a knife, showing my new design.

I claim:—

The ornamental design for a knife, as shown.

GEORGE KOVÁC.

Witnesses:

GEORGE BOLERATZ,
M. W. DICKINSON.
